PNEUMATIC PUMPING SYSTEM

Charles Yeomans, Hubbard Woods, Ill., assignor
to Yeomans Brothers Company, Chicago, Ill., a
corporation of Delaware

Application January 19, 1946, Serial No. 642,243

6 Claims. (Cl. 103—234)

1

This invention relates to a method and an apparatus or system for pneumatically pumping relatively coarse materials such as sewage screenings and the like.

The pneumatic pumping of materials containing a high percentage of liquids, for example raw sewage, by the use of pneumatic ejectors, has been practiced for many years. The usual ejector includes a receiver having inlet and outlet openings, which are adapted to be closed by the use of suitably arranged flap valves, and an air connection which is adapted to be connected either to a suitable source of pressure air or to an air vent. There is also provided control means which is operable in response to the filling of the ejector receiver to close the vent means and to admit air under pressure to the interior of the receiver through the air connection. This air effects the discharge of the contents of the receptacle by pneumatic pumping action, the flap valves being operable to close the receiver inlet and to open the receiver outlet when the pressure is applied. The control means is further operable when the receiver contents have been discharged to shut off the pressure air and to vent the interior of the receiver in order that it may be refilled and the cycle repeated.

The receiver inlet valve is closed during the ejection operation in order to prevent the air pressure from being transmitted to the inlet line, and during the filling operation it is necessary that the inlet valve shall be open and that the outlet valve shall be tightly closed in order to prevent back-flow of the previously discharged material.

Pneumatic ejector systems as described above are reliable and most satisfactory in operation and, as previously stated, have been extensively used for the pumping of materials such as raw sewage. Despite this use and the known advantages of pneumatic ejector type pumping equipment, little use has been made of such systems for the pumping of coarse materials such as sewage screenings, and the principal object of the present invention is to provide a pneumatic pumping system which is capable of efficiently and reliably handling coarse materials of this character.

During the course of my investigation of the problem, I have discovered that coarse sewage screenings of the average type can be successfully and reliably pumped in a pneumatic ejector system, provided that the inlet and outlet openings in the ejector receiver are of large cross-sectional area, and provided that a flow velocity through

2

the inlet and outlet valve openings of at least about two feet per second is maintained during each inflow and outflow operation. This combination of structural and operational characteristics effectively prevents fouling of the inlet and outlet valves with resultant back-flow from the outgoing line or application of pressure to the incoming line.

A further and more specific object of my invention is to provide a pneumatic ejector system in accordance with the above stated principal object, which can be assembled from conventional and available parts. As will hereinafter appear, the objects of the invention are accomplished by the provision of an ejector system which obtains high rates of flow at the outlet valve opening by the use of compressed air in amounts and in pressures obtainable with standard available equipment, but which includes control equipment operable to prevent the filling and cyclic operation of the ejector equipment except when the air supply is completely adequate for accomplishing the desired high speed ejection of the contents of the ejector receiver. The system thus permits the use of air compressors and air storage tanks of moderate dimensions, and, provided that the daily or hourly capacity of the system is adequate to pump all of the material which is to be handled in that period, it makes no difference whether the material to be pumped is delivered to the ejector inlet in relatively large amounts at any particular time. In other words, the apparatus is so arranged that it will receive and will deliver material only as rapidly as it is able to handle that material at the high velocity which I have determined to be required in order to maintain the ejector in operative condition and prevent fouling. The features of the invention and its further various advantages will be made more apparent in the accompanying drawings and the following description of certain illustrative embodiments thereof.

In the drawings.

Fig. 1 is a diagrammatic illustration of a pneumatic ejector system in accordance with the invention; and

Figs. 2 and 3 illustrate certain modifications of the system illustrated in Fig. 1.

The system illustrated in Fig. 1 is designed particularly for pneumatically pumping sewage screenings in accordance with the invention, and also sludge, and a sewage screening chamber of the up-flow type is illustrated in section at 1, the screen or strainer included therein being indicated at 2. Raw sewage is delivered to the chamber 1

below the screen 2 and the liquid portions of the sewage, together with any fine suspended solids, flow upwardly through the screen 2 which is of such mesh that coarse particles contained in the sewage will be trapped below the strainer 2. A pipe line 3 connects with the bottom of the screening chamber 1, which desirably slopes inwardly, for conducting the screenings collected therein to an inspection well 4, and the inspection well 4 is similarly connected by a pipe line 5 to the inlet side of a pneumatic ejector 6. The outlet side of the ejector 6 is connected by additional piping 7 to the inlet hopper 8 of a digester 9 or to any other point to which the screenings are to be delivered by the ejector 6. In order that the ejector may be used for pumping sludge from the bottom of the digester, in accordance with the conventional pumping practice, an additional pipe line 10 is provided for conducting sludge from the bottom of the digester to the inspection well 4.

It is the usual practice to pump screenings and sludge in a system of this type during only a short interval of each day's run, or of each shift period, and to facilitate this, a manually operated valve 11 is provided at the delivery end of the screenings line 3 for controlling the delivery of screenings to the inspection well 4. An elongated operating handle 12 for the valve 11 is provided to permit operation of the valve at the inspection well in conventional manner. The sludge line 10 will be provided with suitable valves and connections so that the sludge may be re-circulated through the digester or may be pumped to settling tanks or elsewhere.

Except for the provision of inlet and outlet openings of large cross-sectional area, the ejector 6 is of conventional design and may be similar to that shown in Winter Patent 2,373,935, which is assigned to the assignee of this invention. The inlet valve 13 used in conjunction with the ejector 6 is preferably of the quick opening, shear-gate, type, and the relative proportion of the valve, ejector receiver, and other parts should be such that the inflow of the material to be pumped by the ejector will take place at a rate of flow at least equal to about two feet per second. Inflow, at this velocity is, of course, relatively easy to accomplish. The problem resides in the obtaining of proper outflow velocity.

The outlet check valve illustrated at 14 is of the hinged flap type and may be similar to the valve shown in the Winter patent. The cross-sectional area of both the inlet and outlet valves must, of course, be sufficient to permit free flow therethrough of the largest size material which the ejector may be called upon to handle.

The compressed air supply used for effecting the operation of the ejector includes an air compressor 15, which may be of the rotary type and which is arranged to deliver compressed air to a storage tank 17 by means of suitable piping 16. A check valve 16a is provided in the line 16 from the compressor 15 to the storage tank 17 in order to prevent back flow of air when the compressor is not running.

Delivery of compressed air from the storage tank to the ejector pot or receiver is most conveniently controlled by means which is responsive to the level of the material contained within the ejector receiver, and various of the conventional control systems for effecting this type operation may be used. The particular apparatus disclosed in the system illustrated in Fig. 1 of the drawings includes an arrangement similar to that shown in the above-mentioned Winter patent. This con-

trol system includes a piston valve 19 which is connected to the pressure air storage tank 17 by a pipe line 18 and is connected to the interior of the receiver by means of pipe line 20 and a terminal section 21 formed integrally with the ejector. The piston valve 19 includes an internal piston which is movable between two extreme positions. In one position the piston valve operates to connect the air line 20 to the ejector to the air storage tank 17 by way of the pipe line 18, and in the other position, the piston valve 19 is operable to close the line 18 and to connect the ejector air line 20 to a vent line 27.

Operation of the piston valve 19 in response to changes in the level of the material contained within the ejector receiver is accomplished by means of a pilot or control valve 25, which is connected to a float provided within the ejector receiver by means of a float rod 22 and linkages 23 and 24. The pilot valve 25 is of the two-position type and is connected to the air supply and to either side of the piston valve 19 by means of suitable pipe lines 26 of small diameter.

When the ejector empties, the float rod 22 moves downwardly and operates the pilot valve 25 to supply air to the piston valve 19 so as to effect the closing of the connection between the air line 20 and the line 18 leading to the air storage tank 17, and to open the connection between the air inlet line 20 and the vent line 27. Similarly, when the ejector fills, the float lifts the float rod 22 and operates the pilot valve 25 to cause the flow of pressure air through the lines 26, which effects operation of the piston valve 19 to the other extreme position. In this position, the air line 20 is connected to the air storage tank, and the connection to the vent line 27 is closed.

It will be apparent that in the system as described, the ejector 6 is in condition to refill immediately following each ejection operation, regardless of the conditions in any other part of the system. In instances where the apparatus is used for pumping screenings or other material available in considerable quantity at intermittent intervals, this inherent capability of the system to initiate immediately an automatic repetition of the operative cycle would be very undesirable. Immediate repetition of the cycle requires, if high flow speed operation in accordance with the invention is to be obtained, that the system include air supply equipment of sufficient capacity to provide air, at the relatively high pressure required, in the very short interval of time which elapses between successive operations of the ejector. The difficulties are cumulative, because in order to avoid clogging, it is desired to maintain flow speeds through the inlet and outlet valves of at least about two feet per second, yet the obtaining of this speed during ejection requires relatively large amounts of high pressure air, and the more efficient the system becomes from the viewpoint of preventing fouling and clogging of the outlet valve, the more likely the system is to become clogged on the next successive operation, due to the smaller total time interval involved in the complete operation.

The system of the invention thus includes, as previously stated, means for positively preventing the refilling and recycling operation of the ejection during any period when there is insufficient pressure air available to effect the discharge of the ejector receiver at the high flow velocities which I employ, in order to permit the use of pneumatic pumping apparatus of this character for the pumping of coarse materials such as sew-

age screenings. This means comprises, in the particular system illustrated, a valve, such as the diaphragm valve 30, which is connected in the ejector vent line 27, and which is connected as by means of a pipe line 29 to the compressor 15 in such relation that the valve is closed whenever the compressor is operating. The pressure to operate the diaphragm valve 30 may be supplied by means of an auxiliary pressure outlet 28 embodied into the compressor apparatus, as shown in my Patent 2,385,905, which was issued on October 2, 1945, or other equivalent arrangements may be used.

The compressor 15 includes a driving motor (not shown) which is controlled by means of a pressure responsive switch 33 connected in pressure responsive relationship to the air storage tank 17 by means of an air line 34. The switch 33 includes a circuit opening and closing element, which may be connected as shown diagrammatically in Fig. 1, to open and to close the electrical circuit 35 from a suitable source of power to the compressor motor through the conductors 31 and 32. The switch 33 will normally be set to start the compressor 15 when the pressure within the air storage tank 17 has dropped a relatively small amount below that required for accomplishing the emptying of the ejector at the desired high speed. Thus, immediately following the initiation of each ejection operation with resultant flow of air from the air storage tank 17 into the ejector receptacle via the piston valve 19 and the air inlet 20, the pressure responsive switch 33 will be operated to start the compressor 17. Immediately pressure will be applied to the diaphragm valve 30 so as to close the vent line 27 from the piston valve 19, and this vent line will remain closed until the compressor has stopped; which, in the normal cycle of operation, will be some time after the contents of the ejector have been pneumatically ejected, and after the piston valve 19 has been operated, in response to lowering of the float connected to the float rod 22, to close the outlet line 18 from the air storage tank and to connect the air line 20 leading to the ejector to the vent line 27.

So long as the vent line 27 is closed, pressure will be maintained within the ejector receiver, and this pressure will hold the inlet valve 13 closed, effectively preventing the inflow of any additional material into the ejector receiver. Moreover, since the opening of the diaphragm valve 30 in the vent line 27 is prevented so long as the compressor is running, any additional inflow is prevented until the air supply has reached the point where another high speed ejection operation can be carried out.

Various other arrangements in accordance with the invention may be employed. For example, in the modified arrangement shown in Fig. 2, the motor driven air compressor 15a is of a more conventional type and lacks the auxiliary pressure air outlet 28 of the compressor 15. The diaphragm valve 30 used in this modified arrangement is operated by pressure air taken from the air storage tank 17 through the pipe line 36 in which there is incorporated a solenoid control valve 37. The valve 37 has two positions and is so arranged that in one position pressure air will be conducted from the storage tank 17 through the pipe line 36 to the diaphragm chamber of the valve 30, thereby closing the valve. In the other position, which is the de-energized position of the valve 37, the portion 36a of the air line leading from the air storage tank 17 to the three-way

valve 37 will be sealed off, and the portion 36b of the air line leading from the valve 37 to the diaphragm valve 30 will be connected to a vent 38.

When the pressure responsive switch 33 is operated, in response to the decrease in pressure within the air storage tank 17 resulting from the initiation of an ejection operation, the electrical circuit therethrough is closed. Thereupon the driving motor for the compressor 15a will be energized, and simultaneously, the solenoid valve 37, which is connected in parallel with the compressor motor, will be energized to close the vent 38 and to admit pressure air to the diaphragm valve 30 so as to close the vent line 27. So long as the compressor is operating, the diaphragm valve 30 will be held closed. After the ejector has completed its operation and further outflow of air from the storage tank 17 is prevented by operation of the pilot valve 25 and the piston valve 19, the compressor 15a will continue to run until the desired air pressure level has been restored within the air storage tank 17. At that point, the pressure switch 33 will operate to open the circuit therethrough, shutting off the compressor motor. Simultaneously, the solenoid valve 37 will operate to vent the diaphragm chamber of the valve 30, thereby opening the vent line 27 so as to relieve the pressure within the ejector receiver and permit the refilling thereof. As in the Fig. 1 arrangement, this system contemplates that operation of the compressor will control the operation of the diaphragm valve 30 in the vent line 27.

At somewhat simpler control arrangement is shown in Fig. 3. In this system, the diaphragm valve 30 has been replaced by an electrically operated valve 41, which is normally open, and the energization of this valve is controlled directly by the pressure responsive switch 33. So long as the pressure within the air storage tank is below the value determined necessary to accomplish the desired high speed ejection of the ejector contents, the valve 41 will remain closed, venting of the ejector receiver will be prevented, and the pressure thus retained within the receiver will prevent the inflow of additional materials. As soon as the pressure within the storage tank 17 has been restored to the desired value, the compressor motor control switch 33 will open. The receiver will then be vented, and the system will be in condition for a new operation.

In each of the systems described in the foregoing, means is provided for positively preventing the refilling of the ejector receiver and cyclic operation of the system, except when pressure air is available at sufficient pressure and in sufficient amounts to assure the ejection of the receiver contents at high speeds. The invention thus permits the assembling of a novel pneumatic ejector pumping system, which is capable of handling very coarse materials without danger of clogging, and which does not require the use of other than ordinary capacity standard compressors or other than standard auxiliary equipment. The features of the ejection system and of the novel method of operation of a pneumatic ejection system which are made possible by the invention are set forth in the accompanying claims.

I claim the following as my invention:

- In pneumatic ejector apparatus adapted for the pneumatic pumping of sewage screenings and other coarse material, a receiver having inlet and outlet openings of large cross-sectional area, a pressure air supply system which includes an air storage tank, means responsive to the level of the material contained within said receiver for con-

necting said air storage tank to said receiver, when said receiver becomes filled, to effect the pneumatic discharge of the contents thereof, a vent means arranged for connection to said ejector to effect the discharge of pressure air therefrom following ejection operations, and means responsive to the air pressure within said air storage tank for closing said vent means when said pressure is below a predetermined value, thereby preventing the escape of pressure air from said receiver and the flow of additional material into said receiver except when the pressure in said air storage tank is above said predetermined value.

2. In pneumatic ejector apparatus adapted for the pneumatic pumping of sewage screenings and other coarse material, a receiver having inlet and outlet openings of large cross-sectional area, a pressure air supply system which includes an air storage tank, means responsive to the level of the material contained within said receiver for connecting said air storage tank to said receiver, when said receiver becomes filled, to effect the pneumatic discharge of the contents thereof, said discharge taking place at a rate of flow through the receiver outlet opening which is at least equal to about two feet per second, provided that the pressure of the air contained within said storage tank exceeds a predetermined minimum value at the beginning of the ejection operation, a vent means arranged for connection to said ejector to effect the discharge of pressure air therefrom following ejection operation, and means operable in response to the air pressure within said storage tank to close said vent means when said pressure is below said predetermined value, thereby preventing the discharge of pressure air from said receiver and the flow of additional material into said receiver, except when the pressure in said storage tank is above said predetermined value.

3. In pneumatic ejector apparatus adapted for the pneumatic pumping of sewage screenings and other coarse material, a receiver provided with inlet and outlet openings of large cross-sectional area and having flap valves for closing said openings, a pressure air storage tank, a compressor connected to said storage tank, means responsive to the pressure within said air storage tank for controlling the operation of said compressor, level responsive, control means operable to connect said pressure air storage tank to said receiver, when said receiver becomes filled, to effect the pneumatic discharge of the contents thereof, said discharge taking place at a rate of flow through the receiver outlet opening which is at least equal to about two feet per second, provided that the pressure of the air contained within said storage tank exceeds a predetermined minimum value at the beginning of the ejection operation, a vent line arranged for connection to said receiver following each ejection operation to effect the venting of pressure air from said receiver, said level responsive control means being operable at the conclusion of each ejection operation to stop the flow of air from said air storage tank into said receiver and to connect said vent line to said receiver, and means responsive to the pressure within said air storage tank for preventing the venting and refilling of said receiver except when the pressure in said storage tank is above said predetermined value.

4. In pneumatic ejector apparatus adapted for the pneumatic pumping of sewage screenings and other coarse material, a receiver provided with inlet and outlet openings of large cross-sectional

area, a pressure air supply which includes an air storage tank and a compressor having a main outlet opening connected to said storage tank and an auxiliary outlet opening, means responsive to the pressure within said air storage tank for controlling the operation of said compressor, level responsive, control means operable to connect said pressure air storage tank to said receiver, when said receiver becomes filled, to effect the pneumatic discharge of the contents thereof at a predetermined high speed, provided that the pressure of the air contained within said storage tank exceeds a predetermined minimum value at the beginning of the ejection operation, vent means arranged for connection to said receiver following each ejection operation to effect the venting of pressure air from said receiver, said level responsive control means being operable at the conclusion of each ejector operation to stop the flow of air from said air storage tank into said receiver and to connect said vent means to said receiver, and pressure responsive means connected to the auxiliary outlet of said compressor for preventing the venting and refilling of said receiver when said compressor is in operation, the pressure responsive means for controlling the operation of said compressor being operable to initiate operation of said compressor when the pressure in said air storage tank drops below said minimum value.

5. In pneumatic ejector apparatus adapted for the pneumatic pumping of sewage screenings and other coarse material, a receiver provided with inlet and outlet openings of large cross-sectional area, a pressure air supply which includes an air storage tank and a compressor having a main outlet opening connected to said storage tank and an auxiliary outlet opening, means responsive to the pressure within said air storage tank for controlling the operation of said compressor, level responsive, control means operable to connect said pressure air storage tank to said receiver, when said receiver becomes filled, to effect the pneumatic discharge of the contents thereof at high speed, said discharge taking place at a rate of flow through the receiver outlet opening which is at least equal to about two feet per second, provided that the pressure of the air contained within said storage tank exceeds a predetermined minimum value at the beginning of the ejection operation, a vent line arranged for connection to said receiver following each ejection operation to effect the venting of pressure air from said receiver, said level responsive control means being operable at the conclusion of each ejection operation to stop the flow of air from said air storage tank into said receiver and to connect said vent line to said receiver, and means including a diaphragm valve which is connected in said vent line and which is arranged to be operated by pressure from the auxiliary outlet of said compressor for preventing the venting and refilling of said receiver when said compressor is in operation, the pressure responsive means for controlling the operation of said compressor being operable to initiate operation of said compressor when the pressure in said air storage tank drops below said minimum value.

6. In pneumatic ejector apparatus adapted for the pneumatic pumping of sewage screenings and other coarse material, a receiver having inlet and outlet openings of large cross-sectional area, a compressed air storage tank connected to said receiver, means operable, when the material contained in said receiver reaches a predetermined level, to admit compressed air from said tank

into said receiver, thereby to effect the discharge of said material through said receiver outlet opening, means including an exhaust valve for venting compressed air from said receiver following each ejection operation, and a control for said exhaust valve which is operable, in response to the pressure in said storage tank, to hold said exhaust valve closed and thereby maintain a positive pressure in said receiver, thus preventing the inflow of material into said receiver through said inlet opening during periods when the pressure in said storage tank is below a predetermined value.
